RADIO RECEIVING APPARATUS

Application filed December 24, 1930. Serial No. 504,566.

My invention deals with what is probably the most important characteristic of the modern broadcast receiver, the fidelity with which the radio set reproduces the programs of a transmitting station.

It is comparatively easy to make a radio receiver sensitive, and selective; these also are two important characteristics of a good radio receiver. However, in attaining these characteristics that feature of the receiver to which my invention applies, namely, fidelity of reproduction, is likely to suffer.

In order that the manner in which my invention functions may be appreciated, it is necessary, first to analyze in some detail the modern broadcast radio receiver and the limitations of its several parts.

Essentially it is made up of a radio frequency amplifier, a detector, and an audio frequency amplifier; of course, there are many other parts such as antenna, power supply, loud speaker, etc., but I shall consider only the first three.

The radio frequency amplifier takes the signal from the antenna, or other pick-up device, and amplifies it several thousand times, before supplying it to the detector. Now, a broadcast signal is made up of a whole band of frequencies and not a single frequency. Thus, if the carrier frequency of the station is 1,000,000 cycles, and a musical program is being broadcast, the station is sending out practically all frequencies between 1,005,000 cycles and 995,000 cycles.

That is, a whole band of frequencies—in this case 10,000 cycles wide, is radiated from the transmitting antenna and picked up by the receiving antenna.

All of these frequencies should be amplified equally well by the radio frequency amplifier but unless special circuit arrangements are made, such is not the fact.

In the drawings, Figures 1, 2, 3, 4 and 5 are curves used in explaining the invention; Figure 6 shows a radio receiver according to the invention; and Figure 7 is another curve for explaining the invention.

In Fig. 1, I have shown the response curve of the ordinary radio frequency amplifier for two different signal frequencies; they are

the so-called resonance curves of the set. There is also shown in Fig. 1, the frequency width of a broadcast signal band over which the radio frequency amplifier should amplify uniformly, namely, 10,000 cycles. It will be seen that for neither signal does the circuit amplify uniformly all of the frequencies involved in the signal, and that the difference in amplification of the various components of the signal is much greater for the lower frequency f_1 than it is for f_2 .

The non-uniformity of amplification throughout the frequency band of a broadcast signal is a defect in the ordinary radio frequency amplifier which is overcome only at the expense of complexity of circuit arrangement and operations, and consequently of the cost of construction. When a set acts to give an amplification which varies appreciably throughout a band of frequencies sufficiently wide to reproduce well an ordinary broadcast program, it may be said to have an amplification response sensibly non-uniform throughout the frequency band of a broadcast signal.

The detector of the modern receiver changes the radio frequency signal into one of audio frequency; after passing through the detector the signal consists only of currents with frequencies of from say 50 to 5,000 cycles per second. This current is then sent through an audio frequency amplifier and here also a non-uniform amplification is obtained. In Fig. 2 is shown a normal response curve for an audio frequency amplifier showing best amplification in the middle of the frequency range and much lower amplification at both high and low frequencies.

This response curve is drawn on the assumption that all of the frequencies are supplied to the audio frequency amplifier with the same amplitude but I now consider that the radio frequency amplifier has amplified the low notes of the signal more than the high notes and so the response of the amplifier, with this defective signal supplied to it is shown in Fig. 3. In dotted lines, the curve of Fig. 2, is duplicated and in full lines is shown the response of the audio frequency amplifier to the output of the detector.

This curve shows an even faster falling off of the high frequency components of the signal than the audio frequency amplifier itself would give. This then is the response curve of the average radio receiver, which has no corrective measures applied.

My invention consists of a proper combination of corrective factors operating on the audio frequency amplifier to make the output 10 of the receiver practically the same over the whole range of useful frequencies.

By utilizing the phenomenon of resonance in the secondary circuit of one of the audio frequency transformers, the response curve 15 can be changed from that of Fig. 3 to the solid line curve of Fig. 4. Here the response of the audio frequency amplifier has been greatly increased in the frequency band just below 20 5,000 cycles and has actually been made greater at 4,500 cycles than it is at 500 cycles. Further the "cut off" frequency, beyond 25 which the audio frequency amplifier gives an appreciable response, has been made much more definite, and lowered from what it was in Fig. 3. This feature of the audio frequency amplifier results in much less tendency for interference between broadcasting stations operating in neighboring channels.

The hump in the response curve, shown at 30 A in Fig. 4, can be accentuated or diminished by making the resonance phenomenon in the secondary circuit of the audio frequency transformer sharp or dull. This is accomplished by giving to the secondary circuit, at 35 the frequency A, less or more resistance as the case demands. By increasing the effective resistance, by eddy currents in the iron core, induced currents in neighboring circuits, or losses in the dielectric between the layers of 40 the secondary winding, the hump at A can be lessened, and at the same time, spread out over a larger frequency range.

To bring up the response of the audio frequency amplifier in the low frequency range, 45 other means must be employed, for it can be seen that the response curves of Figs. 3 and 4 coincide in the lower frequency range. I have found that the same means, properly applied, will give both of the corrections desired.

It has been suggested that a very great inductance be used in the primary of the audio frequency amplifier transformer but when such is attempted, difficulty is encountered in retaining the proper ratio of turns without 50 at the same time losing the resonance response phenomenon analyzed above. I have found that by using a condenser, of proper capacity, in series with an adjustable resistance of proper range, I can alter the response curve 55 of Fig. 4 to that of Fig. 5. In the latter figure, the response curve of Fig. 4 is reproduced in the dotted curve and in the full line curve is shown the equalized response to be obtained when using this additional corrective factor.

In Fig. 6, I have shown a radio receiver

consisting of the radio frequency amplifier indicated by the letters R R A, detector D, and the output of the detector is shown supplying the input circuit of a push pull amplifier indicated at T, which, in turn, supplies 70 power to the loud speaker, not shown.

The low frequency corrective effect comes from this action of the circuit C—R, shunting the primary winding of the audio frequency transformer, and the high frequency 75 corrective effect comes from the action of the circuits C₁, R₁, and C₂, R₂, shunting the secondary windings of the transformer T, in addition to the effect of the C—R circuit, which, by mutual induction between the two 80 transformer windings, has a marked effect in the action of the secondary circuit.

The constants of these corrective circuits applied to both primary and secondary windings of the transformer T, and the amount of 85 mutual inductance between the windings, must be of suitable magnitude and relative proportions, to gain the beneficial effects which make for the difference in the response 90 curves of Fig. 5 and Fig. 3, the latter being the uncorrected response.

I have found that transformers having one mil of unimpregnated paper dielectric between layers in the secondary winding and having about 500 henries of inductance in 95 this winding of #40 B. & S. enamel wire, give about the proper internal capacity and effective resistance to serve for C₁, C₂, and R₁, R₂, of Fig. 6.

In combination with these values of the 100 secondary corrective circuits, I have found that if the primary of the transformer has about fifty henries of inductance, a reasonable value of capacity C is .05 microfarad and for a properly cooperating resistance, R 105 should be variable from 2,000 to 100,000 ohms.

I have found that a value of R, which gives the proper low frequency correction for a 110 radio signal at one limit of the broadcast frequency range is not suitable for a signal at the other end of the broadcast spectrum. In fact, for best results R should be continuously variable and adjusted according to the frequency of the signal being received. The 115 reason for this requirement undoubtedly lies in the difference in the response curves of the radio frequency amplifier as illustrated in Fig. 1, and analyzed in connection with the 120 discussion of this figure.

By using my inventive idea above outlined, it is possible to get an essentially uniform response curve over the whole of the range of useful audio frequencies. Whereas the same result may possibly be attained by other 125 means, these are much more complicated and costly than the apparatus I use.

In Figure 7, I have shown in curve A, the fidelity curve of a modern radio receiver, as it comes from the manufacturer and in the 130

two other curves, B and C, I have shown the response curves of the same receiver, when it is equipped with my corrective circuit, both when this is properly and improperly adjusted.

In curve B, insufficient resistance was used in the corrective circuit so that too much correction was applied in the low frequency range and the defect in the high frequency range was actually augmented. A proper value of resistance in the corrective circuit, however, resulted in the performance given by curve C, which is almost 100 per cent perfect response, in the frequency range from 60 to 5,000 cycles.

Having thus described my invention, what I claim is:

1. In a radio receiving set an audio frequency amplifier having a sensibly non-uniform response throughout the band of useful audio frequencies, an audio frequency transformer circuit in which there is the combination of a secondary circuit effectively resonant to a frequency near the upper end of the audio frequency range and a primary circuit resonant to a frequency near the lower end of the audio frequency range.

2. In a radio receiving set an audio frequency amplifier having a sensibly non-uniform response throughout the band of useful audio frequencies, corrective circuit arrangements which result in the secondary circuit of a transformer of the audio frequency amplifier being resonant for frequencies at the upper limit of the audio range and the primary circuit of the transformer being resonant for frequencies at the lower limit of the audio range.

3. In a radio receiving set an audio frequency amplifier having a sensibly non-uniform response throughout the band of useful audio frequencies, a frequency corrective arrangement consisting of an audio frequency transformer and a suitable condenser, arranged to have two resonant frequencies, one of which lies near the upper limit of the useful audio frequencies and the other near the lower limit of the same.

4. In a radio receiving set an audio frequency amplifier having a sensibly non-uniform response throughout the band of useful audio frequencies, a frequency corrective device consisting of a condenser in series with a variable resistance, said condenser and resistance being connected in parallel with the primary of one of the transformers of the audio frequency amplifier, said condenser being of such capacity as to produce, in conjunction with the primary winding of said transformer, parallel resonance for a frequency substantially at the lower limit of the audio range.

5. In a radio receiving set an audio frequency amplifier having a sensibly non-uniform response throughout the band of use-

ful audio frequencies, a frequency corrective arrangement consisting of an audio frequency transformer, with a suitable condenser arranged to have two resonant frequencies, one which lies near the upper limit of the useful audio frequencies and the other near the lower limit of the same, and a variable resistance arranged to vary the sharpness of resonance at these frequencies.
